CALCULATOR HOUSING

Henry Finkel, Montreal, Quebec, Canada, assignor to
The T. Eaton Company Limited

Filed Feb. 5, 1973, Ser. No. 329,864

Term of patent 14 years

Int. Cl. D14—02

U.S. Cl. D26—5 R

FIG. 1

FIG. 2

FIG. 3

FIG. 4

FIG. 5

FIG. 6

FIG. 1 is a perspective view of a calculator housing showing my new design;

FIG. 2 is a front elevational view thereof;

FIG. 3 is an elevational view taken from the side opposite that shown in FIG. 1;

FIG. 4 is a rear elevational view thereof;

FIG. 5 is a top plan view thereof; and

FIG. 6 is a bottom plan view thereof.

I claim:

The ornamental design for a calculator housing, as shown.
